Int. Cl. D15—08

U.S. Cl. D92—15

FIG. 2.

FIG. 3.

FIGURE 1 is a front perspective view of a tufting machine showing my new design, the machine is shown broken away at the center to indicate indeterminate length;

FIGURE 2 is a rear elevational view thereof;

FIGURE 3 is a top plan view; and

FIGURE 4 is a side elevational view, the side opposite being a mirror image thereof.

This is a continuation of applications D-7892, filed July 20, 1967, and D-7930, filed July 21, 1967, both now abandoned.

I claim:

The ornamental design for a tufting machine, as shown and described.
